UNITED STATES PATENT OFFICE.

JOSEPH WELF, OF CLEVELAND, OHIO.

CUSPIDOR.

SPECIFICATION forming part of Letters Patent No. 242,494, dated June 7, 1881.

Application filed April 22, 1881. (No model.)

To all whom it may concern:

Be it known that I, JOSEPH WELF, of Cleveland, in the county of Cuyahoga and State of Ohio, have invented new and useful Improvements in Cuspidors, of which the following is a description.

This invention relates to an improved mode of constructing sheet-metal cuspidors.

Said improvement consists in a peculiar manner of connecting the upper part or mouth of the article to the lower part or bowl, so that the two sections can be easily and readily taken apart for discharging the contents thereof.

A further improvement consists in providing the cuspidor with a cast-metal base, to which the bowl of the article is secured by being spun thereon and to which casters are attached, substantially as hereinafter described, and illustrated by the annexed drawings, making a part of this specification, in which—

Figure 1 represents an external side view of the cuspidor. Fig. 2 is a vertical transverse section. Fig. 3 is a side view of the metal base of the cuspidor detached from the vessel. Fig. 4 is a plan view of the same.

Like letters of reference refer to like parts in the several views.

The cuspidor above alluded to consists of two detachable sections, A and B, and a cast-metal base, C, to which said section B is secured in a permanent manner, as hereinafter described. Section A is the mouth of the vessel, and B the bowl thereof, both of which are made of sheet metal spun or stamped into shape. The two parts are connected to each other at the throat B by having a screw-thread, a, formed on the collar or neck E of the bowl, and a corresponding thread formed on the collar or neck F of the mouth A. The two collars, thus provided with screw-threads, are united to each other by screwing the collar of the mouth A into the collar of the bowl B, as shown in Fig. 2, thereby making a firm and substantial connection of the two parts to each other, which can be easily and readily unscrewed for emptying the bowl and as readily united again for use.

It will be observed in Fig. 2 that the flaring sides of the upper section or mouth A of the cuspidor is in close contact with the edge of the collar of the bowl by the one being screwed

hard upon the edge of the other. Said edge forms an annular shoulder for supporting the mouth screwed into it; hence there is no looseness at the joint to cause leakage and rattling. 55

G, the bottom of the bowl, is of sheet metal, fitted closely to the inside thereof and above the edge, leaving a flange projecting below it, as seen at b in Fig. 2. Said bottom may be secured in place by soldering or otherwise. 60

The base C, above alluded to, consists of a cast-metal ring transversely curving to form a molding for the base of the vessel, as seen at b. From the upper inner edge of the ring project radial ears e, Fig. 4. On the under side of each 65 of the ears is formed a boss, d, Fig. 2, perforated with a hole for the admission of the shanks of the casters H, loosely fitted therein, and prevented from coming out by having the upper ends headed down in a countersink of 70 the hole, as shown in said Fig. 2. The cuspidor is supported upon the casters and moved about thereon from place to place. This feature of the cuspidor, however, is not new, as casters have long been in use for that purpose. 75 The said ring is secured to the bowl of the cuspidor by being fitted to the inside of the flange b, above alluded to, and in contact with the bottom G, forming an annular support to the bottom in its connection with the bowl, 80 thereby rendering its union therewith strong and permanent.

The lower edge of the flange is rolled under the edge of the ring and turned upward around upon the inside, making a smooth rounded 85 edge, and firmly securing the ring within the flange and in contact with the bottom G, thereby making the base of the cuspidor neat and substantial.

The ring, being of cast metal and of considerable thickness, prevents the sheet metal of the flange from becoming bruised and indented by being pushed or kicked by the feet and at the same time gives an efficient hold for the casters. 90

Instead of attaching the ring to the bowl in the manner above described, it may be secured thereto by forming a collar on the upper edge of the ring, and providing the collar with an annular groove, in which is rolled or spun the edge of the flange. In this event the flange should be made narrower than when 95 100

spun wholly over the ring, as above described. It is preferred, however, to secure the ring to the bowl as first set forth and shown in the drawings.

5 What I claim as my invention, and desire to secure by Letters Patent, is—

1. In combination with the bowl of a sheet-metal cuspidor, a cast-metal base, C, consisting of a ring fitted within the lower part or flange of the bowl, and secured in place by the edge of the flange, and provided with perforated radial ears adapted to receive the shanks of the casters on which the cuspidor is supported, substantially as described, and for the 15 purpose specified.

2. Substantially as herein described and set forth, a sheet-metal cuspidor consisting of the detachable sections A and B, connected to each other by screw-joint, cast-metal base or ring provided with perforated radial ears adapted to receive the shanks of the casters upon which the cuspidor is supported. 20

In testimony whereof I affix my signature in presence of two witnesses.

JOSEPH WELF.
